(57) **CLAIM**

The ornamental design for a screen assembly for conferencing environment, as shown and described.

DESCRIPTION

FIG. 1 is an isometric view of a screen assembly for conferencing environment showing the new design.

FIG. 2 is a front view of the new design; and,

FIG. 3 is a top view of the new design.

The broken or dashed lines shown in the drawings are for illustrative purposes only and form no part of the claimed design.

The shading lines shown in the drawings represent the approximate three-dimensional contour of the design, and are not intended to indicate surface decoration.
